(57) **CLAIM**

The ornamental design for a thermometer case, as shown and described.

DESCRIPTION

FIG. 1 is a front perspective view of an embodiment of a thermometer case showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational thereof; and,

FIG. 8 is a left side elevational view thereof.

In the example embodiment, the thermometer case is made from translucent material.
